UNITED STATES PATENT OFFICE.

FRANK EDWARDS, OF EASTON, WASHINGTON.

PIPE-HOLDER FLUE ATTACHMENT.

1,414,266.

Specification of Letters Patent. Patented Apr. 25, 1922.

Application filed October 7, 1921. Serial No. 506,159.

To all whom it may concern:

Be it known that I, FRANK EDWARDS, a citizen of the United States, residing at Easton, in the county of Kittitas and State 5 of Washington, have invented certain new and useful Improvements in Pipe-Holder Flue Attachments; and I do hereby declare the following to be a full, clear, and exact description of the invention, such as 10 will enable others skilled in the art to which it appertains to make and use the same.

This invention relates to pipe holder flue attachments and the object of the invention is to improve the construction of the pipe 15 holders to permit them to be readily positioned in the flue opening of a chimney and supported therein in such a manner as to prevent the accidental displacement of the stove pipe from the flue opening.

20 A further object of this invention is to improve the construction of stove pipe holders so as to provide a device, which may be permanently attached within a flue and provided with means for supporting one end of 25 the stove pipe in alignment with the flue opening.

A still further object of this invention is 30 to provide a stove pipe holder including a thimble adapted to be positioned within a flue opening, and a clamping band secured to the pipe and having means engaging the thimble for supporting the pipe within the thimble and in alignment with the flue opening.

35 A still further object of this invention is to provide a stove pipe holder, which is equipped with means whereby the stove pipe may be positioned in alignment with the flue opening in a quick and reliable manner.

40 A still further object of this invention is to provide a stove pipe holder capable of removably supporting a stove pipe in alignment with the flue opening in a quick and reliable manner.

45 A still further object of this invention is to provide a stove pipe holder of this character, which will be simple, practical and comparatively inexpensive in construction, and one that can be manufactured and sold 50 at a low cost.

With these and other objects in view, the invention consists in the novel combination and arrangement of parts hereinafter more fully described and claimed.

55 In the drawing:

Figure 1 is a side elevation of my im-

proved pipe holder illustrating the application of the device,

Figure 2 is a longitudinal sectional view taken through the same,

Figure 3 is a transverse sectional view.

Referring to the drawing, the numeral 5 indicates a flue of any ordinary construction, provided with the usual flue opening 6. Removably arranged in the flue opening 6 is a thimble 7, which thimble has an enlarged end 8, which is adapted to removably receive one end of the stove pipe 9 therein. The smaller end 10 of the thimble is adapted to be fitted within the flue opening 6 and is held therein by the spring hooks 11, which engage the inner wall of the flue 5. The spring hooks 11 are secured in the smaller portion 10 of the thimble 7 and extend rearwardly therefrom, and these hooks are secured to the smaller portion at 70 diametrically opposite points by suitable rivets 12 or other suitable fastening means, suitable for the purpose. The smaller portion 10 of the thimble 7 forms a shoulder 13 at its point of connection with the enlarged portion 8 and this shoulder is adapted to 75 abut or engage the outer wall of the flue opening and limit the inward movement of the thimble 7 in the said flue opening.

80 The peripheral edge of the enlarged portion 8 of the thimble 7 is provided with a plurality of relatively spaced integral laterally extending lugs 14, and each lug has secured therein, a hook 15. A split clamping band 16 is adapted to be removably secured to the stove pipe 9 through the medium of the bolt 17 and nut 18, and thus the band may be permanently and rigidly secured to the stove pipe 9. The band is provided with 90 relatively spaced eyes 19, which have secured therein, one end of the coiled springs 20 as at 21. The free ends of the springs 20 are adapted to be removably arranged over the hooks 15, thus placing the springs under 95 tension and normally urging the stove pipe 9 into the enlarged portion 8 of the thimble 7 at all times, and thus holding the stove pipe in alignment with the flue opening 6.

100 In operation, the thimble 7 is first pushed into the flue opening 6 until the hooks 11 engage the inner wall of the flue 5 and the shoulder 13 engages the outer wall of the chimney, thus securing the thimble within the flue opening 6. The band 16 is then 105 rigidly secured to the stove pipe 9 in the manner heretofore described and the springs 110

20 are pulled or placed under tension until their free ends can be lifted over the hooks 15, and thus the stove pipe will always be urged into the enlarged portion 8 of the 5 thimble 7 and permanently held in place against accidental displacement.

What is claimed is:

1. A stove pipe holder comprising a thimble having one end reduced, spring 10 hooks secured to and extending rearwardly from the reduced end of the thimble at diametrically opposite points and adapted to engage the wall of a flue, the peripheral edge of the enlarged end of the thimble being 15 provided with relatively spaced laterally extending lugs, hooks on the lugs, a split clamping band, means for adjustably securing the clamping band to a stove pipe, and springs having one end secured to the clamping band at diametrically opposite points 20 and their free ends removably secured to the

hooks on the lugs of the thimble to retain a stove pipe in the enlarged end of the thimble and against displacement therefrom.

2. A pipe holder comprising a thimble, a 25 stove pipe received by the thimble, outwardly extending ears on the thimble, and tension means secured to the pipe and to the ears.

3. A pipe holder comprising a thimble 30 having an internal shoulder, a pipe received by the thimble, outwardly extending ears on the thimble, and springs detachably secured to the ears and pipe to force the latter against the shoulder.

35

In testimony whereof I affix my signature in presence of two witnesses.

FRANK EDWARDS.
